Primary Examiner — Sandra Snapp

CLAIM

The ornamental design for a removable insert, as shown and described.

DESCRIPTION

FIG. 1 is a top isometric view of an ornamental design for a removable insert;

FIG. 2 is a front elevational view of the removable insert of FIG. 1;

FIG. 3 is a rear elevational view of the removable insert of FIG. 1;

FIG. 4 is an elevational view of a first side of the removable insert of FIG. 1;

FIG. 5 is an elevational view of a second side of the removable insert of FIG. 1, the second side being opposite the first side;

FIG. 6 is a top plan view of the removable insert of FIG. 1;

FIG. 7 is a bottom elevational view of the removable insert of FIG. 1.

The broken lines in the drawings depict environmental subject matter only and form no part of the claimed design.
